SHREDDING MACHINE WITH RECIPROCATING CUTTER PLATE AND ADJUSTABLE FEED CHANNEL HAVING RESILIENT HOLDING MEANS

Herbert Hysmith, Riverside, Calif.

Application October 28, 1946, Serial No. 706,228

8 Claims. (Cl. 146—178)

1

This invention relates to a shredding machine. More specifically speaking, the invention pertains to that type of shredding machine wherein a single, reciprocatory shredding plate is provided with a multiplicity of shredding openings, each of which has a knife edge portion which acts upon the objects which are shredded in such a manner as to remove from them a shred every time said shredding plate is reciprocated.

Although the art to which this invention pertains is in a well developed state, yet there remains room for improvement in regard to simplicity of construction and more particularly in regard to the provision of better means for guiding the objects being shredded to the shredding member.

Accordingly it is an object of the invention to provide an improved arrangement of guide members to cause the objects being shredded to move in a more dependable manner along a straight path toward the shredding plate, at least one of said guide members being mounted in an improved manner rendering it adjustable in a greater variety of positions so that it can be adjusted to guide to the shredding member objects varying greatly in size and shape.

A more specific object of the invention is to provide an improved wire spring for assisting and guiding the article being shredded to the shredding member, said spring having a terminal spur portion which is impaled into the upper portion of such object when it is put into place upon the guiding means, said spur being carried by a swingable arm of the spring and the spring being furnished with one or more loop portions between the arm and the attached portion of the spring, so that the spur part of the arm is permitted to move along a straight path notwithstanding the swinging movement of the radially extending arm which carries said spur part.

Another specific object is to provide a reciprocating shredding plate having through it openings with knife edges which are directed toward the same face of the plate and toward opposite ends thereof, so as to equalize the operating force.

Among other objects are to provide means for more effectively guarding against the operator's hand being cut by the shredding or slicing elements; to provide for a spring pressed follower improved stop means to arrest the movement of said follower toward the cutting means before said means can be damaged by engagement with said follower; and to obtain the foregoing objects and advantages in a machine which can be manufactured at a low cost and sold to the consumer at an inviting price.

Other objects, advantages and features of invention will hereinafter appear.

Referring to the accompanying drawing, which

2

illustrates a preferred embodiment of the invention,

Fig. 1 is a perspective view of the device, the front side thereof being directed toward the observer.

Fig. 2 is a vertical section on line 2—2 of Fig. 1.

Fig. 3 is a horizontal section on line 3—3 of Fig. 1.

Fig. 4 is an enlarged fragmental perspective detail looking at the back side of the device and showing a potato positioned thereon for being shredded. In this view fragments of the shredding plate are broken out adjacent to one of the shredding openings to show more clearly the knife edge at one side of said opening.

Referring in detail to the drawing, the working parts of the machine are supported upon a substantial, flat mounting plate 7 which is shown as being rectangular except for having at its upper end an arcuate handle portion 8, there being a segmental opening 9 under said handle to facilitate manual grasping thereof. Through said plate is a spacious rectangular opening 10 for delivery of the shredded off portions of the potato 11, or other object operated on by the machine.

An upper guide strip 12 and lower guide strip 13 are provided, these strips being horizontal and respectively bordering the upper and lower margins of said opening 10. Said strips are grooved so as slidably to support between them a reciprocatory shredding plate 14 having an operating handle 15 attached to it at one end. Said plate 14 has through it a multiplicity of shredding openings arranged in transverse rows 16 and 17, the holes of adjacent rows being staggered in relation to each other. Each hole of said rows 16 is provided with a knife edge portion 18, all of said knife edge portions of said rows being located at the same side of the various holes in relation to the direction in which the plate 14 reciprocates which, as shown in the drawing, is the side farthest from the handle 15. The holes of the intervening rows 17 are provided with knife edges 19, oppositely directed to said knife edges 18.

The supporting means for objects being shredded is shown as comprising a sheet metal bracket 20 of angle iron shape in cross section, said bracket having a horizontal bed flange 21, a vertical side flange 22, and at its front end a downwardly directed flange 23 whereby it is attached to the back face of the mounting plate 7. Said bracket also has, at its back end, a vertical end flange 24 which carries centrally a rearwardly projecting sleeve 25, a weld 26 being shown securing said sleeve to said flange. Where the sleeve abuts against it said flange 24 is provided with a circular aperture so that the sleeve and apertured part of the flange combine to support a slidable rod 27 which carries at its front end a follower plate 28 having a sharply roughened front sur-

face 29 abuttable against the object to be fed toward the shredding plate 14, said follower plate being urged forwardly by a compression spring 30 coiled around said rod, the back end of the spring abutting against said flange 24. The outer end of the rod 27 carries a handle 31 usable manually to withdraw the follower preparatory to inserting objects to be shredded, and a stop collar 27a which abuts the end of sleeve 25 in time to keep the follower plate 28 from contacting the knife edges 18 and 19 of the shredding plate.

The aforesaid vertical flange 22 of the bracket plate 20 assists in guiding the objects being shredded toward the shredding plate 14, and with the guiding side flange 22 cooperates the end flange 32 of an L-shaped adjustable sheet metal guide plate 33 having along the midwidth of its other limb a slot 34 to receive a screwthreaded pin 35, which adjustably attaches said guide plate to the back face of the mounting plate 7. A winged nut 36 screws onto said pin to clamp the guide plate 33 in its adjusted position after the latter has been either reciprocated or swung about the pin as a pivot.

The aforementioned members 22 and 32 so guide the objects being fed to the shredding plate that they do not deviate horizontally from the path along which they should travel. To prevent said objects from upward displacement a wire spring 37 (see Fig. 4) is provided one end of which forms a downwardly directed spur 38 directable into the upper surface of the object being fed to the shredding means. Said spur is carried by a horizontal radially extending run 39 of said wire spring, a vertically extending run 40 being looped in between said run 39 and the vertical inner run 41 of the spring, the latter run being secured to the mounting plate 7 by any suitable means, shown as an apertured stub shaft 42 which extends through the mounting plate and projects forwardly thereof, where a winged clamping nut 43 is screwed onto it. Hence it will be seen that the wire spring 37 has a double loop intervening between its attached part and its radial, spur-carrying arm 39. Accordingly said wire spring readily yields to allow its spur portion to travel along a straight path during the swinging movement of said arm or run 39.

In order to assist in releasably clamping the wire member 37 in various positions of vertical adjustment a washer or annular spacer 44 is placed around the stub shaft 42 behind the mounting plate 7, so that, by screwing the winged clamping nut 43 down against the front side of said mounting plate the run 41 of said wire is forcibly held against said washer and thus safely held in the selected adjusted position.

Preparatory to putting the device into operation, if objects like potatoes are to be shredded the angular guide plate 33 may be adjusted to the position shown in Fig. 3 wherein its end flange 32 is directed toward such object; but if the potatoes are much smaller than the one shown the clamping member 33 may be adjusted to bring its unflanged end adjacent to the object being operated upon to aid in guiding it toward the shredding plate. In case a much larger object, for example a head of cabbage, is to be shredded, said guard plate 33 may, after its clamping screw 35 has been loosened, be clamped in place in a fully retracted position wherein it will unobstruct the entire delivery opening 10.

The shredding plate 14 is reversible so as to bring its operating handle at either side of the mounting plate 7, hence is conveniently usable

both by right handed and left handed operators.

Owing to the fact that alternate rows of the holes 16 and 17 in the shredding plate 14 have oppositely directed cutting edges, said plate cuts both ways when it is reciprocated. This arrangement of the cutting edges equalizes the amount of manual force required to move the shredding plate back and forth and also lessens the tendency to lateral displacement of the object being shredded.

I claim:

1. In a machine of the kind described, a mounting plate having through it a delivery opening for cut off portions of objects operated upon by the machine, guides carried by said plate adjacent to opposite sides of said opening, a reciprocatory shredding plate supported by and between said guides, said plate having through it a plurality of openings marginal portions of which are laterally deflected and sharpened, thus forming cutting edges, a support connected with said mounting plate to support adjacent to said delivery opening objects while being shredded, spring actuated means connected with said support and positioned to feed such objects toward said delivery opening as the shredding operation proceeds, and a double looped wire spring comprising an upwardly extending wire run, a downwardly extending wire run, and a vertically extending wire run intervening between said upwardly and downwardly extending wire runs, said upwardly extending wire run constituting a mounting run attached to said mounting plate so as to turn about its axis, said downwardly directed wire run having a radially extending run provided with an angularly directed end portion forming a spur positioned to penetrate an object being shredded thus to hold it against the aforesaid support, the looped formation of said wire spring allowing the swinging of said radial arm when the object being shredded is fed along a straight path toward the aforesaid delivery opening.

2. The subject matter of claim 1, and said wire spring being attached to said mounting plate at one side of said delivery opening, and a feed guide at the opposite side of said opening to cause objects being fed to the shredding plate to move along a straight path in relation to their horizontal position, said feed guide comprising an angular guide plate having a long limb furnished with a longitudinal slot, and a combined clamping and attaching means carried by said mounting plate and extending through said slot of said long limb of said angular guide plate, thus rendering said flange of the latter plate horizontally adjustable and also swingable to a remote position to the path of objects being fed to the shredding plate.

3. In a machine of the kind described, mounting means provided with a delivery opening cut-off portions of objects operated upon, guide means connected with said mounting means and positioned to compel objects fed to said opening to move along a straight path toward said opening in regard to their horizontal position, a double looped wire spring one terminal of which is connected with said mounting means and having its other terminal provided with a radially extending run having a downwardly directed spur directable into upper surface portions of objects being fed toward said opening to hold them against upward displacement, the spur-carrying portion of said wire spring being horizontally deflectable to avoid causing the fed ob-

jects to be horizontally deflected from their course, shredding means connected with said mounting means and positioned to shred progressively away objects fed through said opening, said double looped wire spring comprising three vertically extending parallel runs, said one terminal comprising one of said parallel runs, said double loop intervening between its attached part and its radial, spur-carrying arm, and means to releasably clamp said one terminal in various positions of vertical adjustment to the face of said mounting plate toward which shreddable objects are fed so that said terminal spur is deflectable into the upper surface portions of such shreddable objects and the looped formation of said wire spring allows the horizontal deflection of the spur-carrying portion as aforesaid.

4. In a machine of the kind described, a mounting plate having through it a delivery opening for cut off portions of objects operated upon by the machine, guides carried by said plate adjacent to opposite sides of said opening, a reciprocatory shredding plate supported by and between said guides, said plate having through it a plurality of openings marginal portions of which are laterally deflected and sharpened, thus forming cutting edges, supporting means connected with said plate and having a horizontal supporting surface along which objects to be shredded may travel toward said shredding plate, said supporting means carrying a vertical guide plate stationed at one side of the aforesaid delivery opening, an angular guide plate having a long limb furnished with a longitudinal slot and a guide flange carried by one end of said limb for positioning in an opposed horizontally spaced relation to the aforesaid vertical guide plate, and combined clamping and attaching means carried by said mounting plate and extending through said slot of said angular guide plate, thus rendering said flange of the latter plate horizontally adjustable and also swingable to a remote position to the path of objects being fed to the shredding plate so that large as well as small objects may be fed thereto.

5. In a machine of the kind described, a mounting plate having through it a delivery opening for cut off portions of objects operated upon by the machine, a reciprocatory shredding plate carried by said mounting plate in a parallel adjacent relation to said delivery opening, supporting means connected with said mounting plate and having a horizontal supporting surface along which objects to be shredded may travel toward said shredding plate, said supporting means comprising a sheet metal part carrying an end flange in a parallel spaced relation to said mounting plate, an open ended sleeve projecting from that face of said end flange which is farthest from said mounting plate, a manually slideable rod extending through said sleeve and through an opening for it in said end flange, a follower plate carried by said rod, a compression spring coiled around said rod and tending to move said follower plate toward said delivery opening, a stop collar carried by said rod and positioned to arrest the movement of said follower plate before it engages said shredding plate, said supporting means carrying a vertical guide plate stationed at one side of the aforesaid delivery opening, an angular guide plate having a long limb furnished with a longitudinal slot and a guide flange carried by one end of said limb for positioning in an opposed horizontally

spaced relation to the aforesaid vertical guide plate, and combined clamping and attaching means carried by said mounting plate and extending through said slot of said angular guide plate, thus rendering said flange of the latter plate horizontally adjustable and also swingable to a remote position to the path of objects being fed to the shredding plate so that large as well as small objects may be fed thereto.

10 6. The subject matter of claim 5, and said sleeve constituting the sole bearing for said rod.

7. In a machine of the kind described, mounting means provided with a delivery opening for cut-off portions of objects operated upon a spring-pressed follower to feed such objects to said opening, a reciprocatory shredding plate carried by said mounting means in a position to shred objects as they are fed through said opening, said plate having through it a plurality of openings, a part of the marginal portion of the plate around each of said openings being deflected and sharpened thus forming a cutter, said openings extending in rows that extend transversely to the direction of reciprocation of said plate, said deflected edge portions of said openings being deflected toward the same face of the plate and the cutters of alternate rows being directed toward opposite ends of said plate, supporting means connected with said plate and having a horizontal supporting surface along which objects shredded may travel toward said shredding plate, and a looped wire spring comprising a plurality of vertically extending, parallel wire runs, one of said runs constituting a mounting run which is attached to said mounting plate so as to turn about its axis, another of said parallel wire runs having a radially extending run provided with an angularly directed end portion forming a spur positioned to penetrate an object being shredded thus to hold it against the aforesaid support, the looped portion of said wire spring allowing the swinging of said radial arm when the object being shredded is fed along a straight path toward the aforesaid delivery opening.

8. The subject matter of claim 3 and, the last recited means comprising an apertured stub shaft extending through said mounting plate and projecting forwardly thereof, and a clamping nut secured to said projecting portion of said shaft and forcibly holding said one terminal in the selected adjusted position.

HERBERT HYSMITH.
